WIRE FORM BRASSIÈRE

Elias Heller, Brooklyn, N. Y.

Application February 24, 1949, Serial No. 78,053

3 Claims. (Cl. 2—42)

1

This invention relates to new and useful improvements in bust covering garments such as various types of brassières, namely, lone line, bandeau, etc., and corselets, swim suits, halters, etc.

Heretofore, it has been customary to construct bust covering garments with wire forms to assist in maintaining the shape of the garments, maintaining the garment on the wearer, and to give better supporting qualities. However, in all prior constructions it was customary to construct the garments with passages formed between layers of the garments, or between the garment and tapes secured to the garments. These passages were bounded by lines of stitches and the wire forms were engaged therein. With these constructions, the wire forms required ends so that they could be engaged into and through the passages and removed when desired. Said constructions do not permit the wire forms to have completely annular parts extending through 360° and be removed, and therefore said wire forms were not removable in prior garments.

The dominating object of this invention is to construct a bust covering garment with a wire form, which is characterized by a wire form or stiffening frame having a pair of annular portions of 360° each for encircling the breast pockets of the garment in order to better confine the bust to limited positions and to provide superior support both to the garment and to the bust to give the wearer good lines, and yet be readily removable and replaceable. It is proposed to so construct the garment that the stiffening frame rests against the wearer's body without much pressure against the body, without touching the bust, but arranged to assist in supporting cloth flanges which engage the bust to direct the bust to a definite central position giving better support and a better appearance. These cloth flanges will find their own position on the bust without pressure. With this arrangement the garment will be exceptionally comfortable, and therefore not oppressive to the wearer.

Another object of this invention resides in so constructing the bust covering garment that said stiffening frame with its 360° annular portions for encircling the breast pockets is not sewn in passages but is merely placed in open annular spaces in order that it may easily be removed and re-inserted in the garment. Thus when the garment is to be laundered said stiffening frame may be removed. Moreover, one stiffening frame may be used for several garments.

Another object of this invention resides in so

2

constructing the bust covering garment with the said stiffening frame, that the customary foam rubber bust pads may be worn with the garment, if desired, and may be supported within the breast pockets of the garment by said cloth flanges referred to above.

Still further it is proposed to provide the bust covering garment with hooks at the sides of the bust, adapted to engage the annular portions 10 of the stiffening frame for communicating pulls thereto from the garment generated when the garment is engaged about the body, in order that the pulls will be transmitted to the stiffening frame for preventing relative dislocation of the stiffening frame in relation to portions of the garment.

Still further the invention proposes that said prior mentioned cloth flanges have open sides at points adjacent each other. It is proposed that 20 said cloth flanges be mounted upon the backs of the breast pockets of the garment and be arranged in a certain way to form open annular spaces for removably holding said stiffening frame with the annular portions as already 25 described.

A still further object of this invention resides in the provision and construction of a cloth flap on the garment arranged to cover that portion of the stiffening frame which bridges the two 30 annular breast pocket encircling portions and arranged also to cover the open sides of the cloth flanges mentioned in the previous paragraph. It may be advisable to point out that said open sides are used for the purpose of permitting the bridge portion of the frame to connect with the 35 annular portions thereof which are disposed in said annular spaces between said cloth flanges and the breast pockets of the garment.

Another object of this invention resides in constructing the stiffening frame from a single 40 strand of flexible material bent into shape and held with small bands placed at certain points.

Another object of the invention is the construction of a garment as described which is 45 simple and durable and which may be manufactured and sold at a reasonable cost.

For further comprehension of the invention, and of the objects and advantages thereof, reference will be had to the following description and accompanying drawing, and to the appended 50 claims in which the various novel features of the invention are more particularly set forth.

In the accompanying drawing forming a material part of this disclosure:

Fig. 1 is a fragmentary front view of a bust

covering garment, namely a brassière, constructed in accordance with this invention.

Fig. 2 is a fragmentary enlarged horizontal sectional view taken on the line 2—2 of Fig. 1.

Fig. 3 is a fragmentary back view of Fig. 1 disclosing particularly the central area of the garment in the vicinity between the breast pockets thereof.

Fig. 4 is a fragmentary vertical sectional view taken on the line 4—4 of Fig. 3.

Fig. 5 is an elevational view of the stiffening frame, per se, used in the garment.

The bust covering garment, in accordance with one form of this invention, includes a brassière 10, or other type of garment, having a pair of breast pockets 11 each of which projects outwards from a base diameter 12 in the plane of the garment 10. An annular cloth flange 13 is provided for each of said breast pockets 11, and have outside diameters secured to the base diameters 12 of the garment 10 with stitches 14. These annular cloth flanges 13 extend inwards of the base diameters 12 and form annular spaces 15 in the vicinity of the junctions of said cloth flanges 13 and the said breast pockets 11. Said cloth flanges 13 are formed with open sides 16 at points adjacent each other. A stiffening frame 17 having a pair of annular portions 18 engaging in said annular spaces 15, firmly holds said base diameters 12 in formation. The stiffening frame 17 is also provided with a bridge portion 19 which extends through the open sides 16 of the cloth flanges 13 and connects with the annular portions 18 for holding them in relatively fixed positions. The cloth flanges 13 have free inside diameters so that they may be easily flexed outwards in order that said stiffening frame 17 may be pulled out from and pushed back into said annular spaces 15.

Hooks 20 are mounted on said garment 10 and engage into said annular spaces 15 and hook on to the annular portions 18 of said stiffening frame 17 for communicating stretching stresses in the garment to the stiffening frame 17. More particularly, the hooks 20 extend in between the flanges 13 and the breast pockets 11. The hooks 20 are attached to the garment 10 with stitches 21. The outer end portions of the hooks 20 are covered with small pieces of cloth 22 which are secured with stitches 23 to the garment 10. The hooks 20 are located at opposite sides of the stiffening frame 17.

A cloth flap 25 on the garment 10 normally covers said bridge portion 19 of the stiffening frame 17 and also covers the open sides 16 of said cloth flanges 13. This cloth flap 25 has side portions 26 which are attached by lines of stitches 27 to the upper edge portions of said open sides 16 of said cloth flanges 13. The lower edges of the open sides 16 are free. The cloth flap 25 is integral with the garment 10 and is bent downwards from the central portion 10a of the garment which is between said pair of breast pockets 11. More particularly, the portion 10a is formed from a piece of material bent upon itself to provide a front layer 28 and a rear layer 29. Said front layer 28 extends upwards and at the top is bent downwards to form the flap 25. The back layer 29 extends upwards and terminates at the point 30 beneath the flap 25. The sides of the central portion 10a are secured by said stitches 14 to the adjacent sides of the cloth flanges 13 and the breast pockets 11, see Fig. 2.

The stiffening frame 17 comprises a single

strand of flexible material having its end portions bent into said annular portions 18 and terminating at the ends 31 adjacent the bridge portion 19. Fastening elements 32 secure the ends 31 of the single strand of the flexible material against the adjacent portions of the bridge portion 19. These fastening elements 32 comprise merely bands of material 32 wound around the adjacent portions of the stiffening frame and secured in position with cement. Preferably, the flexible material used to construct the stiffening frame 17 comprises a strand of wire covered with flexible rigid type plastic material. Preferably, in cross section the material forming the stiffening frame 17 is oval, or of some other flat shape so that it may easily rest against the body of a wearer.

The operation and use of the bust covering garment may be understood from the following:

20 The stiffening frame 17 may be removed from the garment merely by disengaging the hooks 20 from the annular portions 18 and pulling the annular portions 18 backwards so that the cloth flanges 13 flex and permit passage of said annular portions. After the annular portions 18 are removed from the annular spaces 15, the stiffening frame 17 is moved downwards so as to move the bridge portion 19 out from behind the flap 25. Now the garment may be laundered, or 30 the stiffening frame 17 may be used in another garment of the same type.

The stiffening frame 17 may be replaced by flexing the cloth flanges 13 and reinserting the annular portions 18 into the annular spaces 15 making certain that the bridge portion 19 extends through the open sides 16 of the cloth flanges 13. The bridge portion 18 is now disposed beneath the flap 25 which then covers it up. The hooks 20 are now hooked on to the sides of 40 the annular portions 18.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In a bust covering garment having a pair of substantially conically shaped breast pockets each of which has a base diameter, a flat annular cloth flange for each of said breast pockets, said cloth flanges having unsecured and therefore free inside diameters and also having outside diameters secured to said base diameters, said cloth flanges being positioned in the bases of said breast pockets and forming annular spaces 55 in the vicinity of the junctions of said cloth flanges and said breast pockets, said cloth flanges having open sides at points adjacent each other, a stiffening frame having a pair of annular portions engaging in said annular spaces and being 60 in the bases of said annular spaces, said cloth flanges and said breast pockets, said cloth flanges having open sides at points adjacent each other, a stiffening frame having a pair of annular portions engaging in said annular spaces and being 65 of diameters substantially equal to the outside diameters of said annular spaces in order to firmly hold said base diameters in circular formation, said stiffening frame also having a bridge portion extending through the open sides of said 70 cloth flanges and connecting said annular portions for holding them in relatively fixed positions, said inside diameters of said cloth flanges engaging the breasts of a wearer of said garment in order to make the garment self-positioning on 75 said wearer, and said cloth flanges being flexible

so that they may be easily flexed outwards in order that said stiffening frame may be pulled out from and pushed back into said annular spaces.

2. A bust covering garment as defined in claim 1, including hooks mounted on said garment and disposed within said annular spaces and engaging the outer sides of the annular portions of said stiffening frame for communicating stretching stresses in said garment to said stiffening frame.

3. A bust covering garment as defined in claim 1, including a cloth flap on said garment and normally covering said bridge portion of said stiffening frame and the open sides of said cloth flanges, said cloth flap being attached to the upper edge portions of said open sides of said cloth flanges, and said cloth flap being also integral with said garment and bent downwards from that portion of said garment which is between said pair of breast pockets.
